UNITED STATES PATENT OFFICE

WILLIAM C. PHEBUS, OF BERWYN, ILLINOIS, ASSIGNOR, BY MESNE ASSIGNMENTS, TO
ASSOCIATED ELECTRIC LABORATORIES, INC., OF CHICAGO, ILLINOIS, A CORPORA-
TION OF DELAWARE

TELEPHONE SYSTEM

Application filed June 30, 1930. Serial No. 464,792.

This invention relates to telephone systems in general, and while it is concerned particularly with systems for supplying telephone service on and between railroad trains and between trains and wayside points, certain features have a much wider field of application.

A telephone system of the above general type is disclosed in applicant's co-pending application, Serial No. 411,714, filed December 5, 1929, on which the present invention may be considered as an improvement. One of the main objects of the invention is the provision of new and improved circuits and apparatus for increasing the efficiency of telephone systems of the type mentioned. A feature in this respect is the arrangement for transposing the single conductor comprising the intermediate talking circuit in order to reduce the effect of inductive disturbances from outside sources. Another object of the invention is the provision of simple and reliable circuits for such systems which will operate satisfactorily with existing signalling and control circuits without interfering in any way with the normal functions of such circuits, and which at the same time will be reasonably inexpensive to install and to maintain.

The various features including those above referred to, and others, will be discussed in detail, reference being had to the accompanying drawings of which Fig. 1 shows a telephone set for use on a railroad train; Fig. 2 shows, schematically, the operating principle upon which the intermediate circuit is based; and Fig. 3 shows a section of railroad track equipped with the necessary circuits and switching devices for providing telephone service.

Referring now to Fig. 1 it will be seen that the telephone set consists of a receiving amplifier RA and a transmitting amplifier TA. The receiving amplifier is of the four stage resistance coupled type, and is normally connected to a high impedance winding of the inductor I. The transmitting amplifier is arranged with two stages of amplification the latter being of the push-pull type. A separate low impedance wind-

ing on the inductor I is arranged to be connected to the transmitting amplifier by a switching relay controlled by a key associated with the transmitter or microphone. The inductor is also provided with a third winding for testing purposes, this winding being connected to a manual jack by means of which an ordinary local battery telephone set may be connected up. The inductor which consists of a laminated core of soft iron provided with the three windings above referred to is suspended beneath the locomotive or one of the cars of a train so that the two poles are as near as practical to the conductor 11 which is installed between the rails, sufficient space being allowed so that the inductor will clear any obstruction likely to be found on the tracks.

Referring now to Fig. 2, conductors 13 and 14 represent the two sections of a block circuit inductively coupled by the transformer TR8. The opposite ends of the two sections are connected by transformers TR7 and TR9, respectively, to two telephone sets, which are shown for convenience as being of the ordinary local battery type. The conductors are connected to non-corresponding terminals of the transformer TR8, the opposite terminals of which are connected to ground. This arrangement gives the effect of a transposition.

Assuming now for example that a power line 12 parallels the circuits in question, current flowing in this line will induce a similar current in each of the sections of the telephone circuit. The current in the first section will be induced in the second section through the transposing transformer TR8, and will tend to neutralize the current induced directly in the second section from the power line. Voice currents will be transmitted over this circuit in the following manner: when the transmitter at telephone set TEL is spoken into, the voice currents induced in the left-hand winding of transformer TR7 will be induced in the right-hand winding of the transformer, and current will flow from ground through this winding, over conductor 13, through the left-hand winding of transformer TR8, to ground. Similar cur-

rents will be induced in the right-hand winding of transformer TR8, and thence over conductor 14 and transformer TR9, which connects the line with telephone set TEL1. It will be noted, however, that since the windings of transformer TR8 are connected in transposed relationship the direction of current flow in conductor 13 will be opposite to that in conductor 14, as indicated by the arrows. The final result is that voice currents are transmitted with relatively little loss, while interfering currents are cancelled out, thus producing a relatively quiet talking system. This arrangement can be used equally well with ordinary grounded telephone lines or toll lines.

Referring now to Fig. 3, there is shown a section of railroad track divided into electrically separate blocks. A block circuit consists of the two track rails across which there is bridged a battery at one end and a signal control relay at the other. The relay is normally energized by current flow over the block circuit but becomes deenergized when a train enters the block, as a low resistance circuit path is completed through the wheels and axle of the train. The signal relay of each block is shown although only that of each third block is used in connection with the telephone systems comprising the invention. The various relay spring contacts of the block signalling system have no functions to perform in connection with the telephone system and have, therefore, been omitted from the drawings. The spring contacts shown for relays 23 and 27 are additional springs which are installed on existing signal relays for effecting the switching operations to be explained hereinafter. In addition to utilizing the existing signal relays as above-mentioned, certain of the block circuits are provided with an additional relay, such as the relay 24 or 28, connected in series with the block signalling battery. This relay is given a relatively stiff spring adjustment so that it does not become energized in series with the signal control relay, but does become energized from the increased current flow resulting from the entry of a train into the block.

It has been assumed for convenience that the railroad, to which the telephone system comprising the invention is being applied, is already equipped for block signalling. It is obvious that, if this is not the case, the necessary relay and battery equipment may be installed as shown, omitting however the relays not concerned with the telephone system, such as relays 21, 22, 25 and 26.

It will be noted that the equipment for block A corresponds to that of block D, block B corresponds to block E, and block C corresponds to block F. This relationship is carried out throughout the system, each third block being similarly equipped. Each group of three sections or blocks is provided with

an intermediate circuit consisting of a single grounded line. Under certain conditions, to be explained later, two or more intermediate circuits may be connected together. These circuits provide the talking path between the head and rear end of a train, between separate trains, and between a train and the dispatcher's line.

The single conductor comprising the intermediate circuit is simply a grounded line provided with a transposing transformer in the middle and with transformers at each end for connecting with adjacent circuits. In the preferred embodiment shown, an auxiliary path through the rails is provided, since actual operation has shown this arrangement to be particularly reliable. The rail connections may be omitted, however, and the ground return alone used, or the rail return may be used and the ground connection omitted. In either case the operation of the circuit is substantially that of a grounded line, since in actual practice the track rails are usually more or less heavily grounded. It has also been found that bridging a condenser, such as C, around the insulating members separating adjacent blocks in the same group has a tendency to increase the efficiency of the system, particularly in dry weather when the resistance of the ground connections increases.

A dispatcher's telephone line parallels the track and is equipped at convenient intervals with selecting switches, such as S and S1. These switches, or selectors as they are commonly called, may be of the general type disclosed in United States patent to Hulit, No. 1,221,801 of April 3, 1917. The switches are selectively controlled from the dispatcher's office by means of a sender, such as that shown in the above referred to Hulit patent, and operate to connect up the various intermediate circuits to the dispatcher's line. The dispatcher's line will also be equipped with a telephone set, preferably one of the type disclosed in applicant's co-pending application previously referred to.

The selector arrangement permits the dispatcher to obtain connection with a train at will. In order that the train may call the dispatcher, additional connecting apparatus is provided at certain blocks which is adapted to be controlled from the train. Connection with this apparatus is made by means of a shoe and ramp arrangement which may be of the type commonly used for train control, as described in Bulletin #5 of the American Railway Association Committee on Automatic Train Control, published June, 1929.

Before taking up the description of the operation of the circuits in talking connections, the normal condition of these circuits will first be described. Consider for example the intermediate circuit for a group comprising blocks C, D and E under the assump-

tion that the blocks are unoccupied. Under these conditions relay 27 will be energized instead of deenergized as shown. A circuit may be traced from ground and the parallel condensers C1 at the left end of the block C, contacts 42 and 35 which short-circuit the right-hand winding of transformer T2, conductor 111 which is carried on the track bed between the rails, through the left-hand winding of transformer T1 to ground, and in parallel therewith through condensers C1 to the rails of section D. Inductively connected with this circuit by the transformer T1 is a circuit extending from the common ground and rail connection of block D, right-hand winding of transformer T1, conductor 11, contacts 56 and 62 which short-circuit the left-hand winding of transformer T3, to ground, and also through condensers C1 to the right-hand end of the rails of section E.

It will be seen from the foregoing that the above circuit is entirely separate from the adjacent circuits at either end, due to the short-circuits around the windings of transformers T2 and T3, respectively. The adjacent circuits incidentally are exactly the same as the circuit described, as are also the other intermediate circuits of the system. When block D is occupied by a train, relay 26 will become deenergized with no effect on the above described circuit. This relay is used only for the usual block signalling circuit (not shown). When block E is occupied by a train relay 27 will become deenergized and, in addition to performing its usual block signalling functions which are well known, will remove the short-circuit from the left-hand and right-hand windings of transformer T3 by opening contacts 61 and 62. Relay 27 will also prepare a locking circuit for relay 32 by closing contact 63. Under the above conditions the intermediate circuit of blocks C, D and E and that of the adjacent group including block F will be inductively connected by transformer TR3. When block C is occupied relay 24 will become energized to close a point in the locking circuit of relay 30 which corresponds to relay 32, the utility of which will be described hereinafter. Relay 25 will become deenergized but this relay has no effect on the intermediate circuit.

When block B is occupied the same conditions are set up as described for block E, that is, the intermediate circuit of blocks A and B and the preceding block is inductively connected with the intermediate circuit of blocks C, D and E by the transformer T2. It may be noted at this point that each of the transformers is connected up to give the effect of a transposition as described in connection with Fig. 2. Thus regardless of the number of intermediate circuits connected together the effective circuit always com-

prises an even number of transposed sections.

It will be seen from the foregoing circuit description that as a train moves along a track from left to right on the drawing, the intermediate circuits will be connected up successively so that the head and rear end of the train will always be in inductive relationship with the same intermediate circuit. The various block circuits will normally be longer than the average train and consequently, there will be an overlapping only when the train leaves one group of blocks and enters the adjacent group, such as in passing from block B to C. Under these conditions the two intermediate circuits will be joined to form a single circuit, as described. It is possible, of course, that the block circuits may be relatively short and that a train may overlap more than two blocks in which case the intermediate circuits in (if necessary) three groups of blocks will be inductively connected.

Having in mind the operation of the telephone set (Fig. 1) previously described, it is clear that in operating the transmitter if a train is either standing still or moving through any of the blocks, a current will be induced in the intermediate circuit. This current may be picked up by the inductor of a similar telephone set at a point in any of the blocks concerned in the intermediate circuit. For example, in transmitting from a point in block E the voice currents will be impressed on the intermediate circuit which includes the circuit of blocks C, D and E and those of the adjacent blocks to the right which are connected up by transformer T3. The currents may be picked up in either blocks C, D and E or the three blocks to the right of E and then amplified by the receiving amplifier to operate the associated loud speaker. In this manner communication may be held in both directions from the head end to the rear end of a train or between trains occupying the section of track in question.

It may be noted that the intermediate circuits are normally disconnected from the dispatcher's line. Communication may thus be held between different parts of the train and between trains without interfering with the service over the dispatcher's line.

Should the dispatcher desire to communicate with a train, for example, when the train is occupying block E, as shown, selector S1 will be operated to close the contacts associated with the particular intermediate circuit involved, in this case contacts 59 and 60, thereby closing a circuit for relay 32. Relay 32 on operating will complete a locking circuit for itself by way of contacts 54 and 63, open additional points in the short circuit for the windings of transformer T3 at contacts 55 and 56, and connect the middle winding

of the transformer across the dispatcher's line at contacts 57 and 58. The voice currents induced in the intermediate circuit, as previously described, will thus be impressed on the dispatcher's line through the transformer T3, and similar currents applied to the dispatcher's line will be impressed on the intermediate circuit through this same transformer. This arrangement permits a conversation in both directions as long as the train is in one of the six blocks concerned. The dispatcher will normally allow the selector S1 to remain in its operated position during the conversation, although if this is not done the circuit will be maintained during the time the train occupies blocks E and F, due to relay 32 locking through contact 63 when block E is occupied or through contact 64 when block F is occupied.

It will be seen from the foregoing that by means of the single selector S1 communications may be established with the train in any one of six blocks, regardless of whether or not block F is occupied. The adjacent intermediate circuits will be connected on the operation of relay 32, which opens the short-circuit around the winding of transformer T3, as described. A similar selector S controls the connection of the preceding intermediate circuits to the dispatcher's line in the same manner.

In establishing a connection from a train to the dispatcher's line, key K is operated and, as the train passes the ramp 48, a circuit is closed from battery through the contact of the key, shoe SH, ramp 48, through the winding of relay 31, and through the rail and wheel to the other pole of the battery. Relay 31 on operating completes a circuit for relay 32 at contact 53. Relay 32 energizes and performs the functions previously described, i. e., connects up the adjacent intermediate circuit and connects up the dispatcher's line. Relay 32 will remain locked up as long as the train occupies either of blocks E and F, which provides a sufficient interval to hold the usual conversation. The ramps, such as 47 and 48, may be located at any point along the blocks B and E, respectively. In actual practice, however, these ramps will be located near the right hand end of the concerned blocks in order to eliminate the use of long conductors from the springs of the ramp relay to the associated apparatus.

In order to test the telephone apparatus, the test telephone TT is connected with the test winding of the inductor by means of the plug P and jack J. With key K3 operated, voice currents set up in the test winding when the transmitter is spoken into will be induced in the receiving winding of the inductor and amplified in the usual way. The transmitter is tested with key K2 operated. The amplified voice currents im-

pressed on the low impedance winding of the inductor will be induced in the test winding and will be audible in the receiver of the test telephone. These tests may be applied at any time as the track circuits are not involved in any way.

What is claimed is:

1. The combination, with a railroad track and a train operating thereon, of a closed electrical circuit comprising a single conductor paralleling the track and a ground return, said conductor being inductively transposed with respect to ground at a point substantially equidistant from the ends thereof, and a telephone set on the train inductively connected to said circuit.

2. In a telephone system for communicating between two different points on a moving train or between either of said points and a wayside point, the combination, with transmitting and receiving sets at each point, of an intermediate circuit comprising two inductively connected sections, each of which consists of a single conductor and a ground return, for inductively connecting said telephone sets.

3. In a telephone system for communicating between two different points on a moving train or between either of said points on a wayside point, the combination, with transmitting and receiving sets at each point, of an intermediate circuit comprising a single conductor and a ground return, said conductor being inductively transposed with respect to ground at approximately the mid-point thereof, and means including said circuit for inductively connecting said sets.

4. In a telephone system for communicating between two different points on a moving train or between either of said points and a wayside point, the combination, with transmitting and receiving sets at each point, of an intermediate circuit comprising a single conductor and a ground return inductively connecting the two sets on the train, and means controlled from the wayside point for inductively connecting said circuit with the set at that point.

5. In a telephone system for communicating between different points on a moving train, the combination, with transmitting and receiving sets at each point, of a stationary intermediate circuit comprising a single conductor and a ground return, said conductor being inductively transposed with respect to ground at the midpoint thereof, and means including said circuit for inductively connecting said sets.

6. In a telephone system for communicating between different points on a moving train, the combination, with transmitting and receiving sets at each point, of a plurality of stationary intermediate circuits each comprising a single conductor and a ground return, means controlled by the train

for connecting adjacent circuits in transposed relationship, and means including said connected circuits for inductively connecting said sets.

5 7. In a telephone system for communicating between a moving train and a wayside point, the combination, with a transmitting and receiving set on the train, of a transmitting and receiving set at the wayside point, a wayside circuit, a plurality of separate intermediate circuits each comprising a single conductor and a ground return for connecting said two sets via said wayside circuit, and means for connecting said intermediate circuits together independently of said wayside circuit.

8. In a telephone system for communicating between a moving train and a wayside point, the combination, with a transmitting and receiving set on the train, of a transmitting and receiving set at the wayside point, a plurality of separate intermediate circuits each consisting of a single conductor and a ground return for connecting said sets, and means for connecting said circuits together in transposed relationship.

9. In a telephone system for communicating between two different points on a moving train or between either of said points and a wayside point, the combination, with transmitting and receiving sets at each point, of a plurality of separate intermediate circuits each comprising a single conductor and a ground return for inductively connecting said sets, and means controlled from the wayside point for inductively connecting adjacent ones of said circuits.

10. The combination, with a railroad track divided into a plurality of electrically insulated sections, of separate closed electrical circuits each comprising a single conductor and a ground return for corresponding groups of sections, said circuits being adapted to inductively connect with a telephone set carried by a train occupying any one of the associated track sections, and means for connecting adjacent circuits when sections of two separate groups are simultaneously occupied by a train.

50 11. The combination, with a railroad track divided into a plurality of electrically insulated sections, of separate closed electrical circuits each comprising a single conductor and a ground return for similar groups of sections, said circuits being adapted to inductively connect with a telephone set carried by a train occupying any one of the associated track sections, and means for connecting adjacent circuits when adjacent sections of two groups are simultaneously occupied by a train or trains.

12. The combination, with a railroad track divided into a plurality of electrically insulated sections, of separate closed electrical circuits each comprising a single conductor

and a ground return for similar groups of sections, said circuits being adapted to inductively connect with a telephone set carried by a train occupying any one of the associated track sections, and means automatically operative when a train occupies a particular one of said sections for connecting the circuit associated with the occupied section with the circuit associated with the adjacent group of sections.

70 13. The combination, with a railroad track divided into a plurality of electrically insulated sections, of a separate closed electrical circuit comprising a single conductor and a ground return for each group of sections, said circuits being adapted to inductively connect with a telephone set carried by a train occupying any of the associated track sections, and means for connecting the circuits of adjacent section groups in transposed relationship.

75 14. The combination, with a railroad track divided into a plurality of electrically insulated sections, of a separate closed electrical circuit comprising a single conductor and a ground return for each group of sections, said circuit being adapted to inductively connect with a telephone set occupying any of the associated track sections, and means for connecting the circuits of adjacent section groups so that a current flow in one direction in one circuit will set up a similar current flow in the opposite direction in the other circuit.

80 15. In combination, an inductor comprising an iron core and three separate windings, a receiver connected to the first winding, a transmitter adapted to be connected to the second winding, and a test set adapted to be connected to the third winding for testing both said receiver and said transmitter.

85 16. In combination, a receiver inductively connected with a telephone line by a high impedance winding of an inductor, a transmitter adapted to be inductively connected with said line by a low impedance winding of said inductor, and a test set adapted to be inductively connected with either said receiver or said transmitter by a third winding of said inductor.

90 17. In a system for communicating between a moving train and a wayside point, the combination, with a telephone set at the wayside point, of a line extending from said set along the route followed by the train, a telephone set on the train, a plurality of separate intermediate circuits each comprising a single conductor and a ground return, means controlled from the train for completing a circuit including an intermediate circuit and said line to connect said two telephone sets, and means controlled from the train for connecting a plurality of said intermediate circuits together independently of said line.

120 18. In a system for communicating between a moving train and a wayside point, the com-

bination, with a communication set at the wayside point, of a line extending from said set along the route followed by the train, a communication set on the train, a plurality of intermediate circuits each comprising a single conductor and a ground return and adapted to be inductively connected with the set on the train, and means controlled from either the train or the wayside point for connecting an intermediate circuit to said line to complete a communicating circuit between said two sets.

19. In a system for communicating between two stations on a moving train or between either of said stations and a wayside station, a communication set at each station, a line extending from the wayside station along the route followed by the train, a plurality of intermediate circuits each comprising a single conductor and a ground return and adapted to be inductively connected with the sets on the train, means for connecting certain of said circuits to said line to establish communication between a station in the train and the wayside station, and means for connecting certain of said circuits together independently of said line to establish communication between the stations on the train.

In witness whereof, I hereunto subscribe
30 my name this 27th day of June, A. D. 1930.

WILLIAM C. PHEBUS.
